UNITED STATES PATENT OFFICE.

NORMAN T. HARRINGTON, OF LANSING, MICHIGAN.

EXPLOSION-ENGINE AND METHOD OF OPERATING THE SAME.

1,148,166.

Specification of Letters Patent. Patented July 27, 1915.

Application filed February 8, 1909. Serial No. 476,748.

To all whom it may concern:

Be it known that I, NORMAN T. HARRINGTON, a citizen of the United States of America, residing at Lansing, in the county of Ingham and State of Michigan, have invented certain new and useful Improvements in Explosion-Engines and Methods of Operating the Same, of which the following is a specification, reference being had therein to the accompanying drawings.

10 It is the object of the invention to obtain an explosion engine which is operable with kerosene or other oils less volatile than gasoline, and it is a further object to avoid the 15 use of complicated devices which have heretofore been necessary for forming the explosive mixture with such fuels.

15 The invention consists in the novel means employed in forming and introducing into the explosion chamber the explosive mixture, and, further, in the method of operating the engine whereby satisfactory results are obtained.

20 In the drawing the apparatus is shown in diagrammatic longitudinal section.

25 In the present state of the art, it is usual to provide engines designed for the use of kerosene and other heavy fuels with carbureters which are more complicated in 30 their organization than are employed for gasoline. Generally the oil, or the mixture of the same with air, is preheated before introduction into the cylinder, or, in some cases, the oil is volatilized directly in the 35 explosion chamber by contact with the heated surface and is then mixed with the in-drawn air. Such constructions have not proven thoroughly reliable under practical conditions, and difficulty is frequently experienced both by reason of an imperfectly 40 formed explosive mixture and by the soot-ing and fouling of the spark plug.

45 With the present invention, the explosive mixture is formed and maintained by a totally different method—viz., by dispensing with a preheating or volatilization of the oil and the formation of a cold mixture by finely atomizing the oil and mixing the same with the air, the mixture being introduced 50 in this condition into the explosion chamber.

55 This method produces a more highly combustible mixture than where the oil is preheated but less finely divided, and, furthermore, a heavier charge of cold mixture may be introduced into the cylinder than is possible where the mixture has been diluted by

preheating. I have found however other difficulties to overcome, one of which is the fouling of the spark plug. Thus if the plug is arranged in the usual position—that is, in the direct path of the in-drawn explosive mixture, it will soon become carbonized and rendered inoperative. I have avoided this difficulty by guarding or shielding the spark plug from the direct current, and preferably by shifting its location to a point in the explosion chamber which is removed from the inlet.

60 Still another difficulty to overcome is the accumulation of the oil upon the head of the cylinder during the compression of the mixture, this occurring where the head is water-cooled as is usual with gasoline engines. This may be avoided by dispensing with the water-jacket and permitting the head to 70 become heated to a point above the vaporizing point of the oil, but where this is done another difficulty is encountered—viz., danger of preignition of the compressed charge. I have overcome this latter difficulty by introducing with the explosive mixture a certain quantity of water, the effect being to 75 lower the temperature of the compressed gaseous charge. Thus in my completely reorganized machine the explosive mixture is first formed by finely atomizing the oil and 80 mixing with air in a cold condition; is then introduced into the cylinder, together with a certain quantity of water; is compressed 85 in an explosion chamber having a hot wall, 90 and is ignited from a spark plug which is out of the direct path of the incoming explosive mixture.

95 In carrying out my invention various constructions of apparatus may be employed, but, as illustrated, the mixture is first formed in a carbureter of the "Venturi" type that is, one having a double tapered air induction tube, and the jet nozzle discharging at a point just beyond the smallest diameter of 100 the tube. This carbureter which within certain limits maintains a constant ratio between the air current and the liquid discharged from the nozzle, I use not only for introducing the oil, but also for proportioning the water, and, as shown, A is the oil inlet nozzle centrally arranged within the double tapered tube B, while C is the water inlet nozzle entering from the side of the tube B. Both of these nozzles A and C are 105 controlled by adjustable valves D E so that any desired proportion of ingredients may

be maintained. The first spraying of the oil is effected as it is discharged from the nozzle A, but this is insufficient to finely atomize all of the oil. I have therefore arranged 6 foraminous screens F in the tube B and at intervals in the connected conduit G which lead to the valve chest H and into the explosion chamber I. The latter is formed by a recess in the cylinder head J which is 10 unjacketed and will be heated by the explosions to a relatively high temperature. The spark plug K is located in the wall of the head J at one side of the inlet port L from the valve chest.

15 With the construction as described in operation the suction stroke of the piston will draw in a proportionate charge of air, oil and water into the tube B, and will then force the materials successively through the 20 foraminous screens which break up or atomize the oil and water and cause it to be carried in suspension but in the liquid form in the air current. Upon the compression stroke this charge is compressed between 25 the walls of the head J of said piston M, which after the engine is in full operation are both heated. Thus when the atomized oil comes into contact with these walls it will be vaporized, but at the same time the 30 presence of water in proper proportion will prevent the temperature of the gas from rising to the ignition point. Thus the combined mixture when exploded is composed of mixed air and vapor of oil, together with 35 the minute particles of liquid oil in suspension in the air. The latter will burn without smoke, as under the heat of explosion they are practically instantaneously vaporized.

40 To start the engine, it is preferable to employ a more volatile fuel than the kerosene or other heavy oil normally used, and, as illustrated, the carburetor is provided with a third nozzle N controlled by a valve O 45 and connected with a gasoline supply P. This valve O may be opened in the starting of the engine and the valve D for the kerosene supply closed, and after the walls of the explosion chamber have been heated the 50 valve O is closed and the valve D opened. A second device for starting the engine is formed by a casing Q connected with the explosion chamber and projecting so as to be capable of being heated by a torch. This 55 will furnish sufficient initial heat to make the engine start with the kerosene mixture.

What I claim as my invention is:

1. The method of generating power in explosion engines which consists in forming 60 and introducing into the cylinder a mixture of air and finely divided or atomized heavy liquid fuel held in suspension therein, in compressing the charge in an explosion chamber, the walls whereof are heated materially above the vaporized point of the oil,

in introducing water to limit the temperature of the compressed charge below the igniting point, and in then igniting the charge.

2. The method of operating explosion engines, which consists in forming a mixture of air and heavy hydrocarbon oil, the temperature of the mixture being below the vaporizing point of the oil, in passing said mixture through fine mesh screening to 70 finely atomize the oil, in introducing the mixture into an explosion chamber, the walls of which are of a temperature materially above the vaporizing point of the oil, and in then igniting the charge. 75

3. The method of operating explosion engines which consists in introducing into the explosion chamber a cold mixture of air and finely divided or atomized heavy oil and water, in maintaining the walls of said 80 explosion chamber materially above the vaporizing point of the oil, and in then igniting the charge. 85

4. The method of operating explosion engines, which consists in forming a mixture of air and heavy hydrocarbon oil, the temperature of the mixture being below the vaporizing point of the oil, in passing said mixture through fine mesh screening to 90 finely atomize the oil, in introducing the mixture into an explosion chamber, and in then igniting the charge. 95

5. The method of generating power in explosion engines which consists in forming and introducing into the cylinder, a mixture of air and finely divided or atomized, heavy hydrocarbon oil held in suspension in the air and water, in compressing said charge in an explosion chamber the walls whereof are heated materially above the vaporizing point of the oil, and in then igniting the charge. 100 105

6. The method of generating power in explosion engines which consists in forming and introducing into the cylinder a comparatively cold mixture of air and finely atomized heavy hydrocarbon oil and water held in suspension in the air, in compressing said charge in an explosion chamber, the walls whereof are heated materially above the vaporizing point, and in then igniting the charge. 110 115

7. The method of generating power in explosion engines which consists in forming a mixture of air, heavy hydrocarbon oil and water, the temperature of the mixture being below the vaporizing point of the oil, in passing said mixture through screens of fine mesh to finely atomize the oil and water, in transferring said mixture with the oil in 120 suspension therein into the cylinder, in compressing said mixture in the cylinder the walls whereof are heated materially above the vaporizing point, and in then igniting the charge. 125 130

8. The method of generating power in explosion engines which consists in forming a mixture of air, heavy hydrocarbon oil and water, in passing said mixture through a
5 plurality of screens of fine mesh to atomize the oil and water, the temperature of the mixture being below the vaporizing point of the oil, in introducing said mixture with the oil and water in suspension therein,
10 compressing said mixture in a cylinder, the

walls whereof are materially heated above the vaporizing point of the oil, and in then igniting the charge.

In testimony whereof I affix my signature in presence of two witnesses.

NORMAN T. HARRINGTON.
